UNITED STATES PATENT OFFICE

EARL L. WEAVER, OF GOSHEN, INDIANA, ASSIGNOR TO THE GOSHEN MANUFACTURING COMPANY, OF GOSHEN, INDIANA

DESIGN FOR A LAWN SWING

Application filed January 12, 1931. Serial No. 38,278. Term of patent 3½ years.

To all whom it may concern:

Be it known that I, EARL L. WEAVER, a citizen of the United States, residing at Goshen, in the county of Elkhart and State of Indiana, have invented a new, original, and ornamental Design for Lawn Swing, of which the following is a specification, reference being had to the accompanying drawing, forming part thereof.

The figure is a perspective view of a lawn swing, showing my new design.

I claim:

The ornamental design for a lawn swing, as shown.

EARL L. WEAVER.
